UNITED STATES PATENT OFFICE.

THURE DAHL, OF BROOKLYN, NEW YORK, ASSIGNOR TO LIGHTOLIER COMPANY, OF NEW YORK, N. Y., A CORPORATION OF NEW YORK.

DESIGN FOR A BOWL-HANGER.

53,002.

Specification for Design.

Patented Feb. 18, 1919.

Application filed October 31, 1918. Serial No. 260,612. Term of patent 7 years.

To all whom it may concern:

Be it known that I, THURE DAHL, residing and having my post-office address at #328 73d street, borough of Brooklyn, county of Kings, State of New York, and a subject of the King of Sweden, have invented a new, original, and ornamental Design for Bowl-Hangers, of which the following is a specification, reference being had to the accompanying drawing, forming part thereof.

The figures show a plan view of the front and side of a bowl hanger, showing my new design.

I claim:

The ornamental design for a bowl hanger, as shown.

THURE DAHL.
